UNITED STATES PATENT OFFICE.

EDWARD I. PLOITLE, OF SCRANTON, PENNSYLVANIA.

ARTICLE HOLDER FOR TELEPHONES.

Application filed October 27, 1928. Serial No. 315,572.

This invention relates to improvements in article holders particularly adapted for easy attachment or detachment with the post of a telephone receiver.

5 An object of this invention is to provide a pencil holder for telephone receivers having convenient means for detachably holding a pencil or otherwise.

10 A further object of this invention is to provide a pencil holder adapted to be clamped at a convenient position on the post of a telephone receiver, the holder comprising substantially a single piece of material formed into proper shape for clamping the post, 15 and having a supporting member extending therefrom for holding the pencil in a proper inclined position for easy accessibility.

Another object of this invention is to provide an article holder formed in such a manner that it may be used to advantage for advertising purposes, an advertisement being either stamped or attached in the form of a plate to the device.

Other objects of this invention will appear 25 from the following description of the device and as disclosed in the single sheet of drawings which is herewith made a part of this application.

In the drawings—

30 Figure 1 illustrates a perspective view of a telephone receiver having the pencil holder, according to this invention, in combination therewith.

Figure 2 represents a perspective view of 35 the pencil holder.

Figure 3 illustrates a top plan view of the pencil holder.

Figure 4 represents a sectional view of Figure 3 taken along line 4—4.

40 In the article holding device, according to this invention, it is preferred that numeral 1 designate the post of an ordinary telephone receiver adapted to support in clamped position thereon a pencil holding device, comprising substantially a single piece of suitable material such as sheet metal, formed having a main body portion 2, of proper resilience for clamping around the post member 1.

50 Extending from the lower corner edge of the main body portion 2, and integrally connected therewith, is a supporting shelf member having a downwardly extending portion 3, and a shelf portion 4, which is adapted to 55 extend downwardly at an obtuse angle to the portion 3, in such a manner that when the

clamp is connected with the post 1, the shelf 4 will extend at an angle thereto, as disclosed in Figure 1.

The shelf portion 4 is adapted to have 60 fastened thereto in some suitable manner a coil spring holder 6, having any desired number of coils and spaces 7 therebetween for receiving a pencil 5.

The spring coils may be fastened to the 65 supporting sections 3 and 4, in any suitable manner such as that disclosed in the figures of drawing, wherein openings 8 and 9 are formed in the shelf section 4, through which the loose ends of the coil spring 6 may extend, the ends of the spring 6 being ultimately held in fixed position within the downwardly extending portion 3, as at 11, thereby providing the maximum flexibility for receiving and holding the pencil 5 in such a 75 manner that it can be easily removed from the holder when desired, it being understood that the spring coils extend loosely through the openings 8 and 9, the ends being bent downwardly where they extend through 80 the openings 11, as clearly disclosed at 12 and 13.

The clamping portion 2 of the holder may be provided at its free end with a projection 10, for readily snapping the clamp into position around the post 1, or detaching the device therefrom.

It will be understood that many changes and modifications may be made in the form of embodiment of the invention within the 90 scope of the following claims without departing from the spirit of the invention.

What I claim is:

1. An article holder for a telephone receiver comprising a main body portion 95 formed from a single piece of material having a clamping portion, a bracket integrally extending therefrom, and a spiral member loosely supported on the bracket for detachably receiving the article.

2. An article holder for a telephone receiver comprising a main body portion formed from a single piece of material having a clamping portion, a bracket integrally extending therefrom, a spiral member 105 loosely supported on the bracket for detachably receiving the article, and openings in the bracket for loosely receiving the free ends of the spiral, thereby giving freedom to the movement of the spiral.

3. An article holder for a telephone receiver comprising a main body portion

formed from a single piece of material having a clamping portion, a bracket integrally extending therefrom, a spiral member loosely supported on the bracket for detachably receiving the article, openings in the bracket for loosely receiving the free ends of the spiral, thereby giving freedom of movement to the spiral, the bracket compris-

ing a downwardly extending member integrally formed from the clamping section, and a shelf portion extending downwardly at an obtuse angle therefrom, the shelf portion being adapted to support the spiral member. ¹⁰

In testimony whereof I affix my signature.

EDWARD I. PLOTTLE.
